The ornamental design for a display screen with graphical user interface, as shown and described.

DESCRIPTION

FIG. 1 is a front view of a first embodiment of a display screen; with graphical user interface; and,

FIG. 2 is a front view of a second embodiment thereof. The dashed vertical broken line that extends upward from the topmost open circle forms part of the claimed design. The outermost broken line perimeter illustrates a display screen and forms no part of the claimed design. The remaining broken lines illustrate portions of a graphical user interface and form no part of the claimed design.
